UNITED STATES PATENT OFFICE.

ARTHUR ROBERTS, OF EVANSTON, ILLINOIS.

FUEL-PIPING FOR COKE-OVENs.

1,292,066.

Specification of Letters Patent.

Patented Jan. 21, 1919.

Continuation of application Serial No. 15,287, filed March 18, 1915. This application filed August 5, 1915, Serial No. 43,750. Renewed June 6, 1918. Serial No. 238,603.

To all whom it may concern:

Be it known that I, ARTHUR ROBERTS, a citizen of the United States, residing at Evanston, county of Cook, and State of Illinois, have invented certain new and useful Improvements in Fuel-Pipings for Coke-Ovens and the like, of which the following is a specification.

The present invention has reference to 10 certain improvements in piping which is used for the supply of fuel gas to the burners of coke ovens and the like, and also has reference to improvements in piping for the supply of air to said burners when the 15 air is to be supplied through a system of piping.

The main object of the invention is to make suitable provision for compensation 20 for inequality of expansion of the piping as compared to the expansion of the oven walls themselves with variations of temperature. These inequalities in amount of expansion are occasioned by the fact that the oven walls themselves rise to a very much higher 25 temperature than the piping, and also by the fact that the oven walls and piping have different coefficients of expansion. Each burner should maintain a fixed relationship to the wall of the oven at the point where it 30 delivers its combustible gas. One of the objects of the present invention is to provide flexible connections between the piping and various burners, so that the burners may retain this fixed relationship with respect to 35 various portions of the oven walls, while the manifolds of piping move relatively to the walls, but nevertheless to maintain gas tight connections between the manifold piping and the burners.

Another object of the invention has reference to a simplified arrangement of piping, whereby the gas may be delivered from a single header to all of the burners of a bench of ovens with a minimum amount of 45 piping and with a minimum number of pipes and connections.

In this connection another object is to provide an arrangement for accomplishing the foregoing results, also in those cases 50 where both the air and gas are delivered from headers running along the bench of ovens.

Other objects and uses will appear from a detailed description of the invention which 55 consists in the features of construction and

combinations of parts hereinafter described and claimed.

In the drawings:

Figure 1 shows a front elevation of the upper portions of three adjacent ovens, 60 showing the piping connection for the supply of both air and gas from overhead bench headers to the burners of the various heating walls;

Fig. 2 is a cross section on enlarged scale 65 taken on the line 2-2 of Fig. 3, looking in the direction of the arrows, the lower portion of the section being shifted slightly so as to bring the burners into section;

Fig. 3 is a plan view of a portion of the 70 top of a bench of ovens, showing the arrangement of piping, certain portions of the piping being broken away so as to better show the piping arrangement;

Fig. 4 is a detail elevation of one of the 75 brackets for supporting the manifolds; and

Fig. 5 is a detail section taken on the line 5-5 of Fig. 1, looking in the direction of the arrows.

Fig. 6 is a detail fragmentary view of a 80 modified arrangement of piping in which use is made of certain features of the present invention.

This application is a continuation of my copending application for Letters Patent of 85 the United States, Serial No. 15287, filed March 18, 1915.

In Fig. 1, I have illustrated the upper portions of three ovens numbered 6, 7, and 8, respectively. Each of these ovens is provided with the side heating walls 9 and 10, and the intermediate walls 11 are illustrated as filling in the spaces between consecutive ovens. The construction illustrated in Fig. 2 is substantially that disclosed in Letters 90 95 Patent of the United States No. 1132685, filed by me September 8, 1914, but it will be understood that, as far as the features of the present invention are concerned, I am in no wise limited to the said construction. 100

Along the upper portion of said heating wall, is a row of burners 12. The burner construction illustrated in Fig. 2 is substantially the same as that disclosed in my copending application, Serial No. 875,503, 105 filed December 4, 1914, but as far as the features of the present invention are concerned, any suitable type of burner might be used.

Along the upper portion of one side of 110

the bench of ovens, there are supported the headers 13 and 14. These headers supply air and gas respectively for the various burners. As a convenient means for supporting these 5 headers, I provide the cross arms or brackets 15 on the end struts 16, and then support the headers by the hangers 17. In this way, one header is suspended along each side of the row of struts.

10 Above the space between adjacent heating walls of consecutive ovens, I support the manifolds 18 and 19, respectively. Each pair of manifolds 18 and 19 extends substantially the full length of the oven, and, therefore, extends across substantially the full 15 width of the bench. The manifolds 18 supply gas, and the manifolds 19 supply air to the various burners. Each set or pair of manifolds supply air and gas to a row of 20 burners at each side. This feature is well demonstrated in Figs. 2 and 3. By thus arranging the piping, I am enabled to deliver the air and gas to all of the burners of the bench with a minimum amount of piping 25 and with a minimum number of individual pipes or manifolds. Ordinarily, the charging ports 20 illustrated in Fig. 3 must be reached from a position immediately above each oven. It is, therefore, evident that in 30 many instances it would be very inconvenient to run the manifolds along directly over the carbonizing chambers, so as to supply the air and gas in both directions to burners of the two heating walls of a single oven. 35 I, therefore, illustrate the manifolds 18 and 19 as being mounted over the space between consecutive ovens, so as to supply air and gas to the adjacent heating walls of consecutive ovens instead of to heating walls 40 of the same oven.

Extending downward from the header 14, a downcomer 21 leads directly to each of the manifolds for the supply of air thereto, and the valves 22 are interposed in these 45 downcomers, so that the air supply can be shut off from the manifolds of any oven. Opposite to each oven, I provide a downcomer 23 from the gas header 13, said downcomer in turn leading into a T-connection 24, the arms of which lead sidewise to the manifolds 18 of the corresponding oven. The valves 25 control the supply of gas through the downcomers 23. It is thus evident that the air and gas supply for any 50 given oven may be controlled by the manipulation of one valve 25 and two of the valves 22. With the arrangement of connections just described, I am enabled to deliver the air and gas from the headers to the manifolds of each oven in a very direct manner and with a very simple arrangement of piping, and am also enabled to control the supply of air and gas in bulk to each oven with a minimum number of valves.

60 A pipe 26 leads downward to each one of

the burners. The connections 27 and 28 lead from the manifolds 18 and 19 respectively to these pipes 26, and the valves 30 and 31 control the supply of gas and air respectively to each burner. It is thus possible to individually control the supply of gas and air to the various burners, thus regulating the mixture in each burner, as well as the total combustible mixture delivered to it.

In order to take up the expansion in the 75 manifolds, I have illustrated the following arrangement: Each of said manifolds is preferably made up from a number of sections 32, and at joints 33 where these sections are brought together compressible gaskets may be used so as to permit a certain amount of change in the total length of the manifold by compression of the gaskets. Each pair of manifolds is carried by a row of brackets 34 having the rollers 35 and 36 on which the manifolds are directly mounted, the brackets being supported by the oven walls. In case of any relative movement between the manifolds and oven walls, due to changes in length with expansion and contraction, the manifolds will roll with respect to the brackets. In such case, however, a considerable strain would be thrown on the connections 27 and 28 leading from the manifolds to the burners, 95 and the pipes 26 would be drawn out of line from their respective burners, so that leaks would be occasioned, and the piping structure would be very seriously racked. In order to permit of the necessary relative movement between the manifolds and the pipes 26, I provide the offsets in the pipes 27 and 28 which are well illustrated in Fig. 2. These offsets may be conveniently made up by the use of elbows and nipples, so that 105 when the relative movement occurs, the offsets will twist slightly with respect to the manifolds and with respect to the pipes 26.

In the modified arrangement shown in Fig. 6 each manifold is connected to the proper header by a connection 37, the T-connection 24 being dispensed with.

While I have herein shown and described only a single embodiment of certain features of my invention, still it will be understood that in practice many changes and modifications may be made without departing from its spirit or from the scope of the invention.

I claim:

1. The combination with a bench of coke ovens, each oven having heating walls, of a pair of headers extending along adjacent to the upper portion of one side of the bench, means for supporting said headers in the same horizontal plane, a pair of manifolds extending along adjacent to and above the upper portion of each pair of heating walls, means for supporting each pair of manifolds in the same vertical plane, both of the 120

- headers lying at a greater elevation than the upper manifolds, a connection extending downwardly from the outside header to each of the upper manifolds, connections 5 extending downwardly from the inside header between adjacent pairs of manifolds, a horizontal T-connection from each of the last mentioned downwardly extending connections to the corresponding lower manifolds, and valves for controlling the delivery of gases from the headers to the respective manifolds.
2. The combination with a bench of coke ovens, each oven having heating walls, of a 15 pair of headers extending along adjacent to the upper portion of one side of the bench, means for supporting said headers in the same horizontal plane, a pair of manifolds extending along adjacent to and above the upper portion of each pair of heating walls, means for supporting each pair of manifolds in the same vertical plane, both of the headers lying at a greater elevation than the upper manifolds, a valved connection 20 extending downwardly from one header to each of the upper manifolds, valved connections extending downwardly from the other header between adjacent pairs of manifolds,
- and a horizontal T-connection from each of the last mentioned downwardly extending 30 connections to the corresponding lower manifolds.
3. The combination with a bench of coke ovens, each oven having heating walls, of a pair of headers extending along adjacent 35 to the upper portion of one side of the bench, means for supporting said headers in the same horizontal plane, a pair of manifolds extending along adjacent to and above the upper portion of each pair of heating walls, means for supporting each pair of manifolds in the same vertical plane, both of the headers lying at a greater elevation than the upper manifolds, a connection extending downwardly from one header to one 40 of each pair of manifolds, connections extending downwardly from the other header between adjacent pairs of manifolds, and a T-connection from each of the last mentioned downwardly extending connections 45 to the corresponding remaining manifolds.
